UNITED STATES PATENT OFFICE.

FRANK A. CARR, OF MCKEESPORT, PENNSYLVANIA.

ADJUSTABLE FOOT-REST.

1,091,290.

Specification of Letters Patent. Patented Mar. 24, 1914.

Application filed February 2, 1911. Serial No. 606,112.

To all whom it may concern:

Be it known that I, FRANK A. CARR, a citizen of the United States, and a resident of McKeesport, in the county of Allegheny and State of Pennsylvania, have invented a new and Improved Adjustable Foot-Rest, of which the following is a full, clear, and exact description.

The invention relates to school desks and like furniture, and its object is to provide a new and improved adjustable foot rest arranged to permit of raising or lowering the foot board a desired distance above the floor according to the size of the scholar making use of the desk on which the foot rest is applied, and to allow of folding the foot rest and swinging the same into a vertical position between the standards of the desk and below the table thereof whenever it is desired to dispense with the use of the foot rest or for other reasons.

For the purpose mentioned use is made of a foot board having side arms adjustably secured to standards, base bars adapted to rest on the floor, parallel links connecting the base bars with the said side bars, and a brace adjustably connecting a base bar with a corresponding side bar to lock the parts in the adjusted position.

A practical embodiment of the invention is represented in the accompanying drawings forming a part of this specification, in which similar characters of reference indicate corresponding parts in all the views.

Figure 1 is a perspective view of the adjustable foot rest as applied to a school desk and in position for use; Fig. 2 is a sectional side elevation of the same; Fig. 3 is a like view of the same and showing the foot rest in folded position; and Fig. 4 is a sectional side elevation of the foot rest as applied to standards independent of the school desk.

The school desk on which the rest is applied consists of the usual standards or legs A and the table B supported by the said standards, and the foot rest consists essentially of a foot board C having forwardly-extending side arms D fastened by bolts E to the standards A at the inner sides thereof, as plainly indicated in the drawings. The side bars D of the foot board C are pivotally connected by parallel links F, F' with base bars G adapted to rest on the floor, and each of the base bars G is pivotally connected by a brace H with a corresponding side bar D by the use of a bolt I engaging one of a se-

ries of apertures D' formed on the side bar D. Each bolt E is adapted to engage one of a series of vertically-disposed holes A' formed in the corresponding standard A, according to the position of the braces H relative to the side bars D. The corresponding pairs of parallel links F and F' are connected with each other by cross bars F², F³ so as to strengthen the structure.

In order to adjust the foot board C a desired distance above the floor to suit the convenience of the scholar making use of the desk, the side bars D are disconnected from the standards A by removing the bolts E, and the bolts I are disengaged from the side bars D and the braces H, and then the links F and F' are swung downward or upward until the foot board C is the desired distance above the floor; the bolts I are then reengaged with the corresponding apertures D' and the braces H, to fasten the braces in position, thus holding the parallel links F and F' in locked position relative to the foot board C and the base bars G. The terminals of the side bars D are now fastened by the bolts E to the corresponding apertures A' to fasten the side bars D in place. It is understood that the apertures A' and D' are spaced apart proportionate distances so that the side bars D register with corresponding apertures A' after the foot board C is adjusted the desired height from the floor by adjusting the braces H correspondingly, as above explained. The bolts E may be used as pivots for swinging the foot rest into a vertical position between the standards A and below the table B whenever it is desired to dispense with the use of the foot rest for cleaning or other purposes.

It is understood that the foot board C may be lowered to such an extent by adjusting the braces H correspondingly that the side bars D rest or contact with the base brace G, as indicated in Fig. 3, the foot board C then being in lowermost position, and when swung upward in this position, as shown in Fig. 3, the foot rest takes up very little room and is completely out of the way of the legs of the scholar making use of the desk.

In case the foot rest is to be used in connection with school desks devoid of the apertures A', then use is made of separate standards K, secured to the floor adjacent the standards A, and having apertures K'

for the reception of the bolts E of the foot rest proper, and which is the same in construction as above described in reference to Figs. 1, 2 and 3.

5 The adjustable foot rest shown and described is very simple and durable in construction and can be readily adjusted to bring the foot rest a desired distance above the floor according to the size or stature of 10 the scholar making use of the desk at the time.

Having thus described my invention, I claim as new and desire to secure by Letters Patent:

- 15 1. A foot rest for school desks and the like, comprising a foot board having parallel side bars projecting therefrom for attachment to the standards of a desk, base bars adapted to rest upon the floor, two 20 links pivoted to each end of the foot board and to each base bar, the links at opposite ends of the foot board being connected together, a brace having one end pivoted to

each base bar, and means for adjustably pivoting the other ends of the braces to the 25 side bars of the foot board.

2. A foot rest for school desks and the like, comprising a foot board provided with parallel side bars projecting therefrom for attachment to standards, said bars being 30 provided with a plurality of apertures, base bars adapted to rest upon the floor, two links pivoted to each end of the foot board and to each base bar, a brace having one end pivoted to each base bar, and a bolt 35 passing through the other end of each brace and an aperture of a side bar of the foot board.

In testimony whereof I have signed my name to this specification in the presence of 40 two subscribing witnesses.

FRANK A. CARR.
